(57) **CLAIM**

The ornamental design for a drill-in concrete form tie, as shown and described.

DESCRIPTION

FIG. 1 is a front view of a drill-in concrete form tie according to the present design;

FIG. 2 is a bottom view of the drill-in concrete form tie;
FIG. 3 is an enlarged left side view of the drill-in concrete form tie;

FIG. 4 is an enlarged right side view of the drill-in concrete form tie;

FIG. 5 is an enlarged front view of the left end of the drill-in concrete form tie taken from indication circle 5 of FIG. 1;
FIG. 6 is an enlarged bottom view of the left end of the drill-in concrete form tie taken from indication circle 6 of FIG. 2; and,

FIG. 7 is a perspective view of the drill-in concrete form tie. The broken lines in the drawings illustrate portions of the drill-in concrete form tie and form no part of the claimed design. The drill-in concrete form tie is shown with a symbolic break in its length. The appearance of any portion of the article between the break lines forms no part of the claimed design.

1 Claim, 1 Drawing Sheet
